UNITED STATES PATENT OFFICE.

FRIEDRICH ZIMMERMANN, OF ESSEN, GERMANY, ASSIGNOR TO FRIED. KRUPP AKTIENGESELLSCHAFT, OF ESSEN-ON-THE-RUHR, GERMANY.

CAR REGISTER.

Application filed August 5, 1921. Serial No. 490,114.

To all whom it may concern:

Be it known that I, FRIEDRICH ZIMMERMANN, residing at Essen, Germany, a citizen of the German Republic, have invented 5 a certain new and useful Improvement in Car Registers, of which the following is a specification.

This invention relates to apparatus adapted to register the number of cars passing 10 over a track. Its object is to eliminate the possibility of a fraudulent registration by such an apparatus.

An embodiment of the invention is illustrated by way of example in the accompanying 15 drawings in which:

Fig. 1 is a longitudinal section of the apparatus, built into a railroad track, showing a miner's truck on the track,

Fig. 2 is a plan view of the structure illustrated in Fig. 1, with the truck omitted,

Fig. 3 is a section on line 3—3 of Fig. 2 looking from the right, and

Fig. 4 is a section on line 4—4 of Fig. 2 looking from the right, with, however, the 25 truck as shown in Fig. 1.

On a box-like casing A which is secured on the ties B of a railway track C C¹, there is pivoted on a bolt D a swinging plate E, the width of which, measured in the direction of the track, is greater than the distance 30 between the outer axles of the cars running on the track C C¹. In the illustrated example, the width of the plate E is greater than the distance f² between the axles of the 35 truck F.

The swinging plate E engages with its free end in a recess c², formed laterally in the head of one of the rails, C, which recess limits the swinging movement of the 40 plate E in the direction of the arrow z, Fig. 3. Adjoining the lateral recess c² there is provided in the head of the rail C a trough-shaped recess c³ so that the wheels of the truck F running on the track C C¹ when 45 entering the said recess c³ act upon the plate E in the direction of the arrow z, the weight of the truck tending to cause a rotation of the plate E in said direction. Such rotation is resisted, however, by a spring 50 G (see Fig. 3), the strength of which is such that the plate E can only swing in the direction of the arrow z when all of the axles of the car, in the present case both axles f¹ of the truck F, are supported by

the plate E. This is made possible by dimensioning the plate E as stated above.

On the plate E is mounted a movable pin J, acted upon by a spring H (see Fig. 4). Upon movement of the plate E, in the direction of arrow z, the pin J is caused to contact with a circuit closer K whereby an electrically operated counting mechanism (not shown) is actuated. This contact is accomplished without compressing the spring H completely. Consequently, further movement of the plate E does not affect the pin J, this movement being compensated for by the spring H, thereby protecting the circuit closer K against damage by shocks.

Between the rails C C¹, adjoining the plate E, there is mounted in a casing M, a series of four turnstiles N, of the shape of Maltese crosses, so that they project with one of their arms into the path of the truck axles f¹ (see Figs. 1 and 4). For each turnstile N a pawl P is provided, so arranged that it yields when the turnstile N is turned in a clockwise direction (see Fig. 1) against the action of a spring Q. Movement of the pawls in the opposite direction, and consequently of the turnstiles N is prevented by fixed stop pins m¹. A truck can, therefore, run only in the direction of the arrow z (Fig. 1) over the turnstiles N and therewith over the plate E. The turnstiles N are so located, that, when the truck F is standing on the plate E (see Fig. 1), the truck F is prevented by some of the turnstiles N from being pushed down from the plate E in a direction opposite to that of the arrow z. 90 Also any movement of the truck F onto the plate E from the right in Fig. 1, is prevented by the turnstile N farthest to the right. Consequently a truck can only be run once over the plate E and that in the direction 95 of the arrow z. It consequently follows that it is impossible to accomplish a double counting of a truck by running it back and forth over the plate E.

The operation of the above described device can be readily understood from the foregoing and need not be further described.

Having thus described my invention, what I claim is:

1. In a car registering apparatus, means 105 adapted to be engaged by the car for preventing movement of the car in one direction, a member adapted to be actuated by

the car and means actuated by said member for operating a counting mechanism, said first mentioned means extending beyond both sides of said member in the direction of 5 the track.

2. In a car registering apparatus a member mounted so as to be engaged by the wheels of a car, means operable by said member for actuating a counting mechanism, a ratchet device projecting into the path of the car and comprising a plurality of turnstiles and pawls associated therewith for preventing rotation of said turnstiles in 10 one direction, said ratchet device extending beyond both sides of said member.

3. In a car registering device a ratchet device projecting into the path of the car for preventing movement of the car in one direction, an operating member mounted adjacent the track and enabled to engage all 15 the wheels on one side of a car, said operating member being so shaped and arranged that it will function only when acted upon by all of the wheels on one side of a car and

means controlled by said operating member 25 for actuating a counting mechanism, said ratchet device extending beyond both sides of said operating member in the direction of the track.

4. In a car registering apparatus a ratchet device projecting into the path of the car for preventing movement of the car in one direction, an operating plate pivotally mounted adjacent said track and adapted to be actuated by the wheels of the car, said 30 plate being of such a dimension as to permit simultaneous engagement of all the wheels on one side of a car, means preventing actuation of said plate until engagement of all of the wheels is effected and 35 means controlled by said plate for actuating a counting mechanism, said ratchet device extending beyond both sides of said operating plate.

The foregoing specification signed at Es- 45 sen, Germany, this 2nd day of July, 1921.

FRIEDRICH ZIMMERMANN.
